(57) **CLAIM**

The ornamental design for an air compressor, as shown and described.

DESCRIPTION

FIG. 1 is a first perspective view of an ornamental design for an air compressor showing my new design in a position of use with a handle;

FIG. 2 is a second perspective view of an ornamental design for an air compressor;

FIG. 3 is an opposite side view to that shown in FIGS. 1 and 2;

FIG. 4 is a side view of an ornamental design for an air compressor; and,

FIG. 5 is a top view of an ornamental design for an air compressor.

It being understood that the broken lines are for illustrative purposes only and form no part of the claimed design.
